KNIFE OR SIMILAR ARTICLE OF CUTLERY

Martin F. Zorn, New York, N.Y., assignor to Imperial Knife Associated Companies, Inc., New York, N.Y., a corporation of Rhode Island

Filed Apr. 5, 1961, Ser. No. 64,619

Term of patent 14 years

(Cl. D22—3)

FIG. 1 is a bottom plan view of a knife showing my new design;

FIG. 2 is a side elevational view as seen from the right of FIG. 1, the side opposite thereto being similar in appearance;

FIG. 3 is a top plan view;

FIG. 4 is a blade end view; and

FIG. 5 is a butt end view.

The dominant features of my invention reside in the portions shown in full lines.

I claim:

The ornamental design for a knife or similar article of cutlery, substantially as shown, and described.
